UNITED STATES PATENT OFFICE

142,469

DESIGN FOR A SCARF OR SIMILAR ARTICLE

Joe Brodigan, Brooklyn, N. Y.

Application June 21, 1945, Serial No. 120,232

Term of patent 14 years

(Cl. D3—16)

To all whom it may concern:

Be it known that I, Joe Brodigan, a citizen of the United States, residing at Brooklyn, in the county of Kings and State of New York, have invented a new, original, and ornamental Design for a Scarf or Similar Article, of which the following is a specification, reference being had to the accompanying drawing, forming part thereof.

Figure 1 is an outer plan view of a scarf or similar article, showing my new design.

I claim:

The ornamental design for a scarf or similar article, as shown.

JOE BRODIGAN.
